UNITED STATES PATENT OFFICE.

OLIE M. IRVINE, OF MARSHALL, MISSOURI.

BROOM-BANDING PLATE.

1,125,689.

Specification of Letters Patent. Patented Jan. 19, 1915.

Application filed July 24, 1914. Serial No. 852,869.

To all whom it may concern:

Be it known that I, OLLIE M. IRVINE, a citizen of the United States, residing at Marshall, in the county of Saline and State of Missouri, have invented new and useful improvements in Broom-Banding Plates, of which the following is a specification.

My invention relates to a banding plate for use on broom making machines, in which the broom straw is clamped and held between opposed clamping or banding devices for the application of the banding or binding wires, the object of the present invention being to provide a banding plate which permits of the application of the binding wire with greater ease, expedition and efficiency.

A further object of the invention is to provide a banding plate which is simple, strong and durable of construction, and which admits of the application of the banding wire and the release of the formed broom in a ready and convenient manner, and which is further easily applied to and removed from the jaws of a press and will not interfere with sewing of the broom straws in the usual manner.

The invention consists of the features of construction, combination and arrangement of parts herein fully described and claimed, reference being had to the accompanying drawing in which:

Figure 1 is a front view of a banding plate constructed in accordance with my invention. Fig. 2 is a vertical transverse section of the same. Fig. 3 is a bottom plan view of the banding plate. Figs. 4 and 5 are views showing the application of the invention.

In carrying my invention into practice I provide a banding plate 1, comprising a body portion which is of proper length and width for the purpose, and is longitudinally curved on the arc of an ellipse to properly embrace and shape one side of the broom head to be formed. In practice, a pair of opposed banding plates of the type specified is used, which plates are mounted for relative movement upon the jaws of the broom press for adjustment into and out of position to engage an inserted bundle of straw which is to be formed into the broom head.

The plate has its body portion tapering between its longitudinal edges, as clearly shown in Fig. 2, and its thickened longitudinal front edge is provided with a groove

2 forming a seat recess to receive the wire banding loop. The groove 2 is so formed that its lower wall 3 lies in rear of the plane of its upper wall 4, for a purpose herein after described.

At its ends the longitudinally curved banding plate is provided with end pieces 5 projecting beyond the concaved lower face of the plate, said end pieces terminating in inwardly projecting retaining flanges 6 projecting inwardly at an oblique angle thereto. The flanges slope from front to rear at an angle to provide wedging or binding surfaces 7.

In the use of the banding plates, which are made in lefts and rights, the banding plates are applied to the jaws 8 of a broom press 9, of that type in which the jaws are vertically adjustable to engage the broom head at desired elevations and are also movable toward and from each other to clamp and release the broom head. I have not deemed it necessary to illustrate or describe such a press in detail, as the press itself constitutes no part of my invention. The jaws 8 have their bearing surfaces arranged to slope at an angle to properly bear against the opposite sides of the broom head, and their upper faces are outwardly and downwardly inclined, and said jaws are provided with projecting end lugs 9'. The banding plates are arranged to rest against the upper inclined faces of the jaws with their grooved edges facing inwardly, the inclination of the plates being such that the walls 3 and 4 of the groove 2 of each banding plate lie in the same vertical plane and parallel with the surface of the broom head.

The end pieces 5 of each banding plate project downwardly on the outer sides of the lugs 9', while the retaining flanges 6 extend beneath said lugs and bind against the same to hold the banding plate in position. The banding plate is slipped from a point inwardly of the jaw over upon said jaw, so that the inclined or cam surfaces of the flanges 6 will bind against the insides of the lugs, thus firmly retaining the banding plate in position in such manner that the greater the pressure falling thereon the firmer the banding plate will be retained in position. This construction not only adapts the banding plate to be firmly held without the use of auxiliary fastenings, but also adapts the plate to be easily and conveniently applied and removed.

When the banding plates are arranged in position for operation and the jaws 8 are open the banding wire 10, in the form of an elliptical loop, and made from a piece of 5 wire whose ends are welded together, is disposed between the banding plates and fitted at its sides in the grooves thereof. The straw composing the broom head is then inserted downward through the wire loop 10 until the portion to be embraced by the loop comes in proper position, after which the jaws are forced together to compress and clamp the binding loop in position, and the jaws then retracted to release the broom 15 head for removal or for adjustment of the jaws to a different elevation to apply another banding loop at a different point. By the construction described one or more banding loops may be applied to the broom 20 head in a ready and convenient manner, while allowing the usual operation of sewing the broom straws together to be performed, the sewing being carried out at a point above the level of the banding plates, 25 so that the latter will not interfere with this operation. The banding plates may be conveniently removed at any time for the substitution of other banding plates or for the use of ordinary sewing plates, without the 30 necessity of adjusting or removing any fastenings.

I claim:—

1. A banding plate for broom making machines comprising a body having a longitudinally extending groove to receive a banding wire, one of the walls of said groove being depressed with relation to the other.
- 35 2. A banding plate for broom making

Copies of this patent may be obtained for five cents each, by addressing the "Commissioner of Patents, Washington, D. C."

machines comprising a longitudinally curved body tapered between its concave and convex edges, said plate being formed with a longitudinally extending groove, one of the side walls of said groove being depressed with relation to the other side wall thereof. 40

3. A banding plate for broom making machines comprising a longitudinally curved body having right angular end pieces terminating in flanges extending inwardly at oblique angles, said body being provided with a longitudinally extending wire receiving groove, one of the side walls of said groove being depressed with relation to the other side wall thereof. 45

4. A banding plate for broom making machines comprising a plate body, having an edge portion provided with a groove to receive the banding wire, and having means thereon for interlocking engagement with the jaw of a broom press without the use of extraneous fastenings. 50

5. A banding plate for broom making machines comprising a plate body having an edge portion provided with a receiving groove, the upper and lower walls of said groove being disposed in different planes, 65 end pieces upon the body, and angularly disposed retaining flanges extending inwardly from said end pieces and adapted for a wedging engagement with surfaces of a broom making machine. 70

In testimony whereof I affix my signature in presence of two witnesses.

OLLIE M. IRVINE.
